PUMPING APPARATUS

John Mann, Seneca Falls, N. Y., assignor to
 Goulds Pumps, Inc., Seneca Falls, N. Y., a corporation of New York

Application February 25, 1944, Serial No. 523,927

35 Claims. (Cl. 103—5)

1

My invention relates to liquid pumping apparatus or water systems, particularly suitable for use, for example, in homes or buildings removed from city or village water supply.

An object of my invention is to provide an improved water system which is reliable in operation, compact, and which may be produced at a reasonable cost.

Another object of my invention is to provide a water system which, depending upon conditions under which the system is to operate, may readily be converted to a straight self-priming centrifugal pump, a shallow well pumping system of the jet type or a deep well water system of the jet type.

Another object of my invention is to provide a jet-centrifugal pumping system in which the centrifugal pump is mounted in an air separating chamber, with the base for the air separating chamber and the centrifugal pump serving as a housing for the jet pump when the system is used as a shallow well pump.

Another object of my invention is to provide improved means for supplying the system with air so that the system may be maintained under pneumatic pressure.

A further object of my invention is to provide a water system in which the centrifugal pump is housed within an air separating chamber, and means are provided within the air separating chamber for supplying air to the air separating chamber without passing through the centrifugal pump.

My invention further contemplates the provision of a water system comprising a self-contained unit employing a centrifugal pump, a jet pump, and an air separating chamber which encloses the centrifugal pump, with the system being arranged so that it can be used either with or without the conventional pneumatic storage tank, depending upon the conditions of operation encountered.

Other objects and advantages of my invention will be apparent from the following description, when taken in connection with the accompanying drawings, in which:

Fig. 1 is a vertical sectional view showing the system of my invention arranged for shallow well operation, in which the path of flow of the liquid has been indicated by arrows;

Fig. 2 is a view similar to Fig. 1 showing the air pump for supplying air to the air separating pump;

Fig. 3 is a side view of the unit shown in Fig. 2;

Fig. 4 is a sectional view showing the air pump and the connections thereto with the air pump

2

parts in the position they occupy when the centrifugal pump is operating;

Fig. 5 is a view similar to Fig. 4 showing the position of the air pump parts when the centrifugal pump is at rest;

Fig. 6 is a top plan view of the base of the unit with the system arranged for shallow well operation and with the liquid flow indicated by arrows;

Fig. 7 is a view similar to Fig. 6 with the system arranged for deep well operation and with the liquid flow indicated by arrows;

Fig. 8 is a sectional view similar to Fig. 1 showing the system arranged for deep well operation, the arrows indicating the liquid flow, and

Fig. 9 shows the unit as it is arranged when employed with a conventional pneumatic storage tank.

In Figs. 1 to 6, inclusive, I have shown the liquid pumping apparatus or water system of my invention arranged for shallow well operation. The unit comprises, as shown in Fig. 1, a centrifugal pump generally indicated by the numeral 11; a motor 12 for driving the pump directly connected thereto; an air separating chamber 13 in which the centrifugal pump is mounted; a base 14 for supporting the pump, motor, and air separating chamber; and a jet pump generally indicated by the numeral 16, mounted in the base.

As is well known in the art to which this invention applies, water drawn from the well or other source of supply passes through the jet pump to the suction of the centrifugal pump. It is then discharged by the centrifugal pump into the air separating chamber from which a portion flows to the point of use while the remainder is recirculated through the jet pump to provide energy to aid in lifting water from the well.

The base of the unit, as shown most clearly in Figs. 1 and 6, is preferably a single casting and houses the jet pump 16 and other elements of the system. A suction pipe 17 is threaded into either of two oppositely disposed openings 18 provided in the base casting. The two openings 45 constitute means whereby the suction pipe may be connected to either side of the unit so as to enable a convenient arrangement of the piping, depending upon the location of the unit.

The opening 18 to which the suction pipe is 50 not attached is closed by a plug 19. A substantially tubular compartment 21 is provided in the base casting for housing a strainer 22 through which the liquid flows. The strainer removes larger particles of foreign material which may be drawn into the suction pipe. From the com-

partment 21 the liquid flows to a valve chamber, generally indicated by the numeral 23.

The valve comprises a seat 24 which may be pressed into an opening provided in the base casting and a circular valve element or plate 26. 5 The valve element 26 is normally pressed into engagement with its seat by a spring 27. A cover plate 28 overlies the valve and upon removal of screws 29 access may be had to the valve. The cover plate 28 has a bored boss 31 which confines the spring and provides a guide for a valve stem 32 which is secured in any suitable manner to the valve plate 26. The valve plate 26, in general, may be of any suitable construction but preferably comprises a rubber or somewhat resilient disc which is provided with a metal back-10 ing plate.

The valve spring is preferably relatively light so that no great force is required to lift it off its seat. This force is supplied by the reduced pressure produced by the combined action of the jet pump and the centrifugal pump on the upper side of the valve, together with the pressure on the under side of the valve resulting from the pressure of air applied on the surface of the liquid in the well or other source of supply. At the same time the spring should be sufficiently stiff so that it will aid in holding the valve firmly on its seat and prevent leakage of liquid back through the system into the well when the pump is stopped. Moreover, the spring should be capable of holding the valve on its seat should, for any reason, the pressure in the air separating chamber drop substantially to that of atmosphere. After passing through the valve the liquid flows, as shown in Fig. 6, through a passage 33 to the jet pump 16.

The jet pump 16 comprises a diffuser 36 and a nozzle 37 which are in spaced axial alignment with each other. These parts are of conventional construction and the dimensions and proportions thereof are dictated in accordance with good engineering practices to meet the conditions for which the unit is designed. The diffuser 36 is threaded into a wall 38 provided in the base casting and the nozzle 37 is threaded into a wall 39 also provided in the base casting.

Liquid is supplied from the air separating chamber under pressure. The pressure energy thereof is converted in the jet into velocity 50 energy. The velocity of the jet or stream passing across the space between the tip of the nozzle and the entrance of the diffuser entrains air or liquid adjacent the jet stream and induces a flow of air or liquid from around the nozzle body and creates a vacuum which draws the air or liquid through the passage 33 and into the diffuser. In the diffuser the velocity energy is at least partially reconverted into pressure energy. The liquid or mixture of liquid then flows to a passage 41 provided in the base casting and through a passage 42 to the suction 43 of the centrifugal pump.

The passage 42 is formed by a wall 44 somewhat circularly shaped in section and a wall 46 which forms half of the centrifugal pump casing 41. The other half of the centrifugal pump casing is formed by a member or wall 48 bolted or otherwise secured to the wall 46. A volute passage or passages 49 are formed in the wall 48 70 into which liquid is discharged by the impeller 51. The pump impeller 51 has the eye or suction inlet opening 43 and is threaded or pressed on the end of a shaft 52 by which it is rotated.

An annular seat 53 is provided on the wall 46 75

or inner surface of the pump casing against which is adapted to seat an annular sealing ring 54 which is substantially L-shaped in section. A spring 56 suitably confined against rotation urges the sealing ring 54 into engagement with the seat so as to prevent excessive flow of liquid from the pump casing to the suction of the impeller. The pump casing has at least two discharge openings, one of which 58 (Fig. 2) is shown, the function and construction of which are reserved as the subject matter of a separate application. It is sufficient to state that the centrifugal pump is self-priming and has the ability to handle liquid or a mixture of liquid and air.

The liquid or mixture of liquid and air discharged into the air separating chamber is appreciably slowed down in velocity due to the relatively large volume of the separating chamber. The air is separated out from the liquid and rises to the top of the chamber. Liquid for feeding the jet pump is supplied from the air separating chamber, as indicated by the arrow 59 (Fig. 1), through an opening 61 provided in the base casting which connects with the air separating chamber, as shown most clearly in Fig. 6. The liquid flowing to the jet pump is substantially air free, due to the fact that opening 61 is at the bottom of the air separating chamber to which the heavier liquid gravitates while the lighter air tends to separate from the liquid and rise to the top of the chamber.

Extending upward in the air separating chamber 13 is a liquid level pipe or discharge outlet 62 which is connected, as shown in Fig. 6, to a passage 63 formed in the base casting. Threaded into the base casting is a discharge pipe 64 which carries the liquid to the point of use. The liquid level pipe 62 has a gooseneck 66 at its upper end, as shown most clearly in Fig. 3. The purpose of the gooseneck is to draw the liquid from the air separating chamber at a point well below the normal liquid level and below the discharge openings from the pump casing. At the lower end of the gooseneck or point of entrance of the liquid into the liquid level pipe, the liquid is relatively quiescent and air at this point has substantially entirely separated from the liquid. At the top of the liquid level pipe 62 is a pair of openings 67 (Fig. 1) the purpose of which will later appear.

At the top of the chamber is an opening (Fig. 3) through which a priming pipe 68 is extended. The priming pipe is welded to the margins of the opening to provide an airtight joint at 69 and extends downward into the chamber preferably to a point somewhat above the top of the liquid level pipe. A removable plug 71 is threaded into the top of the priming pipe and forms an airtight joint with the annular end of the pipe when in seated position.

When the system to be initially primed the plug is removed and liquid poured into the priming pipe until the liquid in the system reaches approximately the level indicated at 72, or perhaps slightly higher. It will be appreciated that when initially primed to the level indicated at 72 the pressure in the chamber will be substantially that of atmosphere. In practice the system would be primed so that the liquid rises to the top of the priming pipe, then the air at the top of the air separating chamber will be slightly compressed and the liquid level will lie slightly above that indicated at 72.

The system, as will be presently described, is

provided with a pressure control which starts and stops the motor when the pressure within the air separating chamber reaches predetermined upper and lower limits. Moreover, the system is provided with means for supplying the air separating chamber with air. In the preferred form of the invention the pump supplies the system with a predetermined volume of air each time the pump is stopped. Should the volume of air supplied be somewhat in excess of that required, the liquid level in the air separating chamber, when the pressure therein is at or near the pressure control cut-in point, will be perhaps at the line indicated by the level at 72. The continued supply of excess air to the chamber will cause the level to gradually lower so that when the pressure in the chamber is low, the openings 67 may be uncovered. This permits excessive air to escape from the system with the liquid through the openings 67.

The openings 67 thus prevent an excessive amount of air from accumulating in the system, the excess air readily passing through the openings, mixing with the liquid, and passing out the discharge pipe. At the same time the liquid is trapped in the system to maintain the system primed since it can not leak past the check valve 26 (Fig. 1) and can not drain out the discharge pipe below the level 73 or effective top of the liquid level pipe.

As shown most clearly in Figs. 4 and 5, I have provided novel means for supplying the air separating chamber with air. This in the preferred form of the invention comprises a pump, generally indicated by the numeral 76. The pump 76 comprises a cylinder 77 and a cylinder 78 which may, if desired, be cast integral with the wall 44 which forms part of the entrance channel 42 of the eye of the impeller. A cap 79 provides a channel 81 communicating with the suction passage 42 which is extended upward, as indicated at 82, above the eye of the impeller.

A piston 80 is mounted in the cylinder 77 and comprises a cup leather 83 retained in position by backing plates 84 and 86. Any suitable means for assembling the piston on a piston rod 87 may be provided. The arrangement may be similar to that shown in the drawings. The end of the piston rod is threaded to receive the parts and the cup leather is pressed between a nut 88 and the backing plate 86.

The piston rod 87 at its lower end is provided with a piston 90 and is threaded to receive an element 89 into which is threaded a nut 91. Between the elements 89 and 91 a cup leather 92 is pressed. The cup leather on its upper surface is not confined adjacent its outer periphery so that air may leak in an upward direction past the cup leather, as will presently appear. Rib 93 integral with the casting has an opening 94 through which the rod 87 passes. A spring 96 is confined between the rib and the top of the threaded element 89. The spring 96 normally urges the rod 87 and the pistons in a downward direction.

The lower end of the cylinder 78 has a threaded opening adapted to receive a tube 97 which is fitted with a check valve of any suitable type adapted to admit air from the atmosphere when a vacuum exists in the cylinder. The effective volume of the cylinder 78 is calculated so that its actuation each time the pump stops supplies air to the system somewhat in excess of that required. The excess air escapes from the system in the manner described above.

When the pump is in operation, a vacuum or

lowered pressure is created at the eye of the impeller which is effective through the passages 82 and 81 to create a vacuum or lowered pressure at the top of the piston 80.

10 The lower side of the piston 80 is exposed to the pressure existent within the air separating chamber, since the bottom of the cylinder 77 is open thereto. Since this pressure is substantially that of the discharge of the centrifugal pump, a differential in pressure exists across the piston when the centrifugal pump is in operation corresponding to the differential in pressure across the impeller. This differential in pressure moves the piston to an upward position against the action of the spring 96 or to the position shown in Fig. 4.

15 The upward movement of the piston 80 carries with it the piston 90 which creates a vacuum in the cylinder 78 and opens the check valve 97 to draw air from the atmosphere into the cylinder.

20 The parts will remain in this position as long as the pump is operating. However, as soon as the pressure in the air separating chamber builds up to the cut-out point, the pump is stopped and the pressure is equalized throughout the system back to the check valve 26. That is, when the pump is stopped, liquid is free to flow back through the pump casing, past the impeller blades to the suction of the pump and through the passages 82 and 81. Thus the pressure on opposite sides of the piston 80 is equalized and the spring 96 forces the piston assembly downward to the position shown in Fig. 5.

25 During the downward movement of the piston 90, the check valve 97 is closed and the air is gradually compressed in the cylinder 78. When the pressure is sufficient, air leaks past the cup leather 92 into the air separating chamber. If desired, a leakage opening might be provided between the lower end of the cylinder 78 and the air separating chamber. However, the arrangement shown is preferable. An opening between the cylinder 78 and the air separating chamber would have to be small in diameter so that when upward movement of the piston 90 occurs, air would pass through the check valve 97 into the cylinder 78 before the liquid could flow into the cylinder from the air separating chamber.

30 With the arrangement shown, the cup leather 92 is retained tight against the side walls of the cylinder 78 by the pressure of liquid in the air separating chamber until the air pressure in the cylinder 78 is sufficient to allow escape or flow of air past the cup leather 92 into the air separating chamber. This air then bubbles up through the liquid to the air space at the top of the chamber.

35 One particular advantage of the means shown for supplying air to the system is that the pistons, together with their cup leathers, are located in the air separating chamber. Thus the cup leathers are always immersed in liquid which prevents them from drying out and losing their effectiveness. Moreover, the backing plate 86 is provided with an annular edge 98 which seats against an annular surface 99 provided on the cover plate 79. This, together with the fact that the pressure within the air separating chamber, seals the cup leather 83 against the side walls of the cylinder 77, prevents leakage of liquid from the air separating chamber past the piston 80 to the suction of the centrifugal pump when the pump is operating. Of particular advantage is the fact that air is supplied to the system without passing through the centrifugal pump.

40 Referring again to Fig. 1, it will be noted that the pump is provided with a mechanical seal in-

stead of the usual stuffing box. This seal may be of any suitable type and comprises a spring 101 and a sealing element 102 which seals against an element 103 fixed with respect to the pump casing. Any suitable type of bearing assembly may be provided for the shaft 52. In the drawings, I have shown a sleeve bearing 104 which is adapted to support the shaft and take the thrust load imposed by the impeller. The particular bearing employed constitutes no part of my present invention.

The shaft 52 extends through an opening provided in the wall of the air separating chamber in which opening there is welded, as indicated in the drawings, an annular plate 106 which has a flange 107. An annular ring 108 is bolted to the flange 107, as indicated at 109, and a flexible diaphragm 111 is confined between these parts, as shown in the drawings. The bearing housing 112 extends outward through the opening in the air separating chamber to provide an annular surface 113 against which the flexible diaphragm is placed. An annular ring 114 is bolted, as indicated at 116, to the end of the bearing housing and the flexible diaphragm is confined between these parts.

The above arrangement allows for a slight misalignment of the motor shaft with respect to the pump shaft 52, and at the same time leakage of liquid is prevented from the air separating chamber. Moreover, while a slight misalignment is permitted, because of the support afforded by the end of the bearing housing, the flange and the annular rings 108 and 114, the diaphragm is capable of withstanding pressures substantially above those which may be encountered in the air separating chamber.

The shaft of the motor 12 is connected to the pump shaft 52 by means of a flexible coupling, generally indicated by the numeral 117, which comprises a flexible tube 118 having at the motor end an annular sleeve 119 internally of the tube and an annular band 121 externally thereof. One or more set screws 120 are provided which extend through the annular band, the flexible tube and the sleeve 119 and engage the shaft so that the flexible tube is driven when the motor shaft is rotated.

The other end of the flexible tube is provided with an annular sleeve 123 and an annular band 122 which by suitable screws are connected together to clamp the flexible tube between them. The annular sleeve 123 is connected to the pump shaft 52 by means of a Woodruff key 124. When it is desired to disconnect the parts, the motor 12 may be loosened from its support and the motor, together with the flexible coupling, shifted to the right, as viewed in Fig. 1, so as to disengage the driving connection between the shafts. A removable shield 126 substantially encloses the coupling.

The pressure in the system is controlled between upper and lower limits by means of a pressure switch, generally indicated by the numeral 127, which is subjected to the discharge pressure or the pressure within the air separating chamber through a pipe connection 128.

As shown in Fig. 3 the connection 128 is made into the base adjacent the discharge pipe 64. The pressure switch may be of conventional design adapted to start the motor when the pressure in the air separating chamber drops to a predetermined value, for example, twenty pounds, and stop the motor again when the pressure in the air separating chamber reaches a value of,

for example, thirty-two pounds or any other desired value.

In the drawings I have shown a special type of pressure switch (electrical connections to the motor not shown) which is not the subject of the present invention. Since conventional pressure switches may be employed with the system of my invention which are well known in the art to which this invention applies, the particular means for controlling the starting and stopping of the motor need not be more particularly described in this application.

One of the major advantages of the pumping system of my invention is that it may be readily converted from a shallow well system to a deep well system. In Figs. 7 and 8 I have illustrated now how the shallow well system previously described may be converted to a deep well system. The passage 41 has an opening 129 which is closed by a plug 131 when the system is employed as a shallow well unit.

When the system is converted to deep well operation, the plug 131 is removed and the suction pipe 132, extending into the well, is connected into the opening 129, as indicated in Figs. 7 and 8. This arrangement brings the end of the suction pipe close to the suction of the centrifugal pump impeller so that flow of liquid from the well is substantially direct thereto. The jet pump 16 is removed and a plug 133 substituted in the opening 38 for the diffuser 36. The opening 39 is left open so that flow from the air separating chamber passes through this opening. The cover plate 28 is removed and the check valve 26 taken out of the base casting. The cover plate is then restored to its position and a pressure pipe 134 connected to the base casting, as shown in Fig. 7.

The flow of liquid is then, as indicated by the arrows 136, down the pressure pipe to the jet pump located in the well. Since the arrangement of the pressure pipe, the jet pump and the suction pipe in the well, is well known in the art to which this invention applies, these parts are not shown. However, it will be understood that the tail pipe of the assembly is provided with the conventional foot or check valve. The general arrangement of a deep well pumping system is shown in my prior Patent No. 2,257,507 issued September 30, 1941. With the parts of the system thus rearranged the system will operate as a conventional deep well pump without any change in the manner of connecting the discharge pipe from the system, the pressure control switch, or the air volume control or air pump previously described. Flow of liquid to the point of use is, as in the shallow well unit, through passages 63 and 64.

If it is desired to employ the system as a straight centrifugal pump, a plug is inserted in the opening 39 with the general arrangement being as shown in Fig. 7. The jet pump in the well and the pressure pipe 134 are removed. Liquid is then drawn through the suction pipe 132 into the impeller and discharged into the air separating chamber from whence it flows, in accordance with the demands of the system, out of the discharge pipe 64.

The arrangement of parts shown in Fig. 6 may also be employed as a straight centrifugal pump by removing the nozzle and diffuser and inserting a plug in the nozzle opening 39. The opening 38 is left open giving a straight flow of liquid from the suction pipe 17 to the suction of the centrifugal pump.

The system may be operated without the conventional pneumatic storage tank. However, under certain conditions a pneumatic pressure tank of large capacity is required for storage. These conditions are for example, when the flow of water from the well or other source is insufficient and below the capacity of the pump and the intermittent peak requirements of the user, or when the electrical facilities available limit the horsepower of the motor and hence the capacity of the pump which may be used.

In Fig. 9 I have shown the system arranged with a large pneumatic storage tank. The unit above described is connected by means of a pipe 137 which extends to the pneumatic storage tank 138 at a point preferably near the bottom thereof. Liquid is drawn from the storage tank as required through a pipe 139 which extends to the service lines.

One of the important features of the system of my invention is that the unit above described requires no modification to adapt it for use with a pneumatic storage tank. The pressure switch may be retained on the air separating chamber, as shown, although if desired the pressure switch might be connected to the pneumatic storage tank. Moreover, the air pump is retained as part of the unit and air is supplied to the pneumatic storage tank from the air separating chamber. That is, the air pump is designed to provide air at a rate slightly in excess of requirements. This air gradually accumulates in the air separating chamber and occasionally during the operation pressure in the air separating chamber drops to a low point. When this occurs, the openings 67 (Fig. 3) will be exposed so that air will pass from the air separating chamber to the pneumatic storage tank. Thus air for the pneumatic storage tank is supplied from the air separating chamber.

It will be noted that the centrifugal pump assembly is supported independently of the air separating chamber although both are supported by the base casting. A gasket 141 is interposed between the bottom of the pump casing, the wall 44 and the top of the base casting. A gasket 142 is interposed between the flange formed on the bottom of the air separating chamber and the top of the base casting. The air separating chamber is held in position by studs 143 and lugs 144. With this arrangement access to the pump may be readily obtained by renewal of the studs 143, the guard 126 and bolts 109 and 116. The motor is shifted to the right as viewed in Fig. 1, after which the air separating chamber may be shifted to the right so that the inner edge of the flange 106 clears the end of the bearing housing 112. The air separating chamber may then be removed and access gained to the pumping unit.

While I have shown and described the preferred form of my invention, it will be appreciated that various changes and modifications may be made, particularly in the form and relation of parts, without departing from the spirit of my invention as set forth in the appended claims.

I claim:

1. A pumping system comprising, in combination, a pump casing, an impeller mounted in said casing, means for rotating said impeller, a chamber in which said casing is mounted, said casing having at least one opening through which said impeller discharges liquid into said chamber, and means for supplying air to said chamber without passing through said pump.

2. A pumping system comprising, in combination, a pump casing, an impeller mounted in said casing, means for rotating said impeller, a chamber in which said casing is mounted, said casing having at least one opening through which said impeller discharges liquid into said chamber, and means within the chamber for supplying air to said chamber without passing through said pump.

3. A pumping system comprising, in combination, a pump casing, an impeller mounted in said casing, means for rotating said impeller, a chamber in which said casing is mounted, said casing having at least one opening through which said impeller discharges liquid into said chamber, and means actuated by variations in pressure across the impeller for supplying air to said chamber.

4. A pumping system comprising, in combination, a pump, a pneumatic pressure chamber into which said pump discharges, pressure responsive means actuated by variations in pressure across the pump when operating and when stopped for supplying air to said chamber, and means within the chamber for maintaining the quantity of air in the chamber below a predetermined maximum.

5. A pumping system comprising, in combination, a pump casing, an impeller mounted in said casing, a chamber in which said casing is mounted, said casing having at least one opening through which said impeller discharges liquid into said chamber, a base upon which said chamber rests, a jet pump mounted in said base, the base having passages connecting the jet pump with the source of supply, the chamber and the suction of the impeller.

6. A pumping system comprising, in combination, a pump casing, an impeller mounted in said casing, a chamber in which said casing is mounted, said casing having at least one opening through which said impeller discharges liquid into said chamber, a base upon which said chamber rests, a jet pump mounted in said base, the base having passages connecting the jet pump with the source of supply, the chamber and the suction of the impeller, and means for maintaining a supply of air in said chamber.

7. A pumping system comprising, in combination, a pneumatic pressure chamber, a pump having an impeller for supplying liquid to said chamber, a piston actuated by variations in pressure across the impeller, and means including a valved connection to atmosphere actuated by said piston for supplying air to said chamber.

8. A pumping system comprising, in combination, a pneumatic pressure chamber, a pump having an impeller for supplying liquid to said chamber, a piston actuated by variations in pressure across the impeller, means including a valved connection to atmosphere actuated by said piston for supplying air to said chamber, said liquid pump and piston being located within and enclosed by said chamber.

9. A pumping system comprising, in combination, a pressure pump having a rotatable impeller, an air separating chamber into which said pressure pump discharges, means for supplying air to said air separating chamber, means for normally maintaining a volume of air in said air separating chamber at the top thereof under pressure, a pneumatic pressure tank connected to said air separating chamber, and means for supplying liquid and air to said pneumatic pressure tank from said air separating chamber.

10. A pumping system comprising, in combination, a pressure pump having a rotatable impel-

75

11

ler, an air separating chamber into which said pressure pump discharges, means for supplying air to said air separating chamber without passing through said pressure pump, means for normally maintaining a supply of air in said air separating chamber under pressure, a pneumatic pressure tank connected to said air separating chamber, and means for supplying liquid and air to said pneumatic pressure tank from said air separating chamber.

11. A pumping system comprising, in combination, a pressure pump having a rotatable impeller, an air separating chamber by which said pressure pump is enclosed into which said pressure pump discharges, means for supplying air to said air separating chamber, means for normally maintaining a volume of air in said air separating chamber at the top thereof under pressure, a pneumatic pressure tank connected to said air separating chamber, and means for supplying liquid and air to said pneumatic pressure tank from said air separating chamber.

12. A pumping system comprising, in combination, a pump casing having a rotatable impeller mounted therein, a chamber by which the pump casing is enclosed and into which liquid is discharged from said casing by the impeller, means for normally maintaining a supply of air and liquid under pressure in said chamber, and means for insuring the retention of a sufficient volume of liquid in said chamber to maintain the pump flooded under all normal conditions of operation.

13. A pumping system comprising, in combination, a pump casing having a rotatable impeller mounted therein, a chamber by which the pump casing is enclosed and into which liquid is discharged from said casing by the impeller, means for normally maintaining a supply of air and liquid under pressure in said chamber, and means for insuring the retention of a sufficient volume of liquid in said chamber to maintain the pump flooded under all normal conditions of operation, said means including a discharge connection for said chamber, the effective outlet of which is above the axis of rotation of the impeller.

14. A pumping system comprising, in combination, a pump casing having a rotatable impeller mounted therein, a chamber by which the pump casing is enclosed and into which liquid is discharged from said casing by the impeller, means for initially priming said chamber to a predetermined level after which compression of air takes place above said level, means for normally maintaining a supply of air and liquid under pressure in said chamber, and means for insuring the retention of a sufficient volume of liquid in said chamber to maintain the pump flooded under all normal conditions of operation.

15. A pumping system comprising, in combination, a pump casing, an impeller mounted in said casing, means including a prime mover for rotating said impeller, a chamber in which said casing is mounted, said casing having at least one opening through which said impeller discharges liquid into said chamber, means for starting and stopping the prime mover between upper and lower pressure limits to define a cycle of pump operation, an air supplier for the chamber, and means for actuating the air supplier at least once during each cycle of operation of the pump.

16. A pumping system comprising, in combination, a pump, a pneumatic pressure chamber into which said pump discharges, pressure responsive means actuated by variations in pressure across

12

the pump when operating and when stopped for supplying air to said chamber, and means for maintaining the quantity of air in the chamber below a predetermined maximum.

17. A pumping system comprising, in combination, a pump casing, an impeller mounted in said casing, means including a prime mover for rotating said impeller, a chamber in which said casing is mounted, said casing having at least one opening through which said impeller discharges liquid into said chamber, means for starting and stopping the prime mover between upper and lower pressure limits to define a cycle of pump operation, an air supplier for the chamber, and means for actuating the air supplier at least once during each cycle of operation of the pump, said air supplier being arranged so as to supply air to the chamber without passing through said pump.

18. A pumping system comprising, in combination, a pump casing, an impeller mounted in said casing, means including a prime mover for rotating said impeller, a chamber in which said casing is mounted, said casing having at least one opening through which said impeller discharges liquid into said chamber, means for starting and stopping the prime mover between upper and lower pressure limits to define a cycle of pump operation, an air supplier for the chamber, and means for actuating the air supplier at least once during each cycle of operation of the pump, said air supplier being arranged so as to supply air to the chamber without passing through said pump, and means for maintaining a substantially constant quantity of air in said chamber.

19. A pumping system comprising, in combination, a pump casing, an impeller mounted in said casing, means including a prime mover for rotating said impeller, a chamber in which said casing is mounted, said casing having at least one opening through which said impeller discharges liquid into said chamber, a jet pump, connections for supplying liquid to said jet pump from said chamber and for discharging liquid from said jet pump to said impeller, means for starting and stopping the prime mover between upper and lower pressure limits to define a cycle of pump operation, an air supplier for the chamber, and means for actuating the air supplier at least once during each cycle of operation of the pump, said air supplier being arranged so as to supply air to the chamber without passing through said impeller or jet pump.

20. A pumping system comprising, in combination, a pneumatic pressure chamber, a pump having an impeller for supplying liquid to said chamber, means for starting and stopping the pump to define a cycle of pump operation, an air supplier for said chamber, and means for actuating said air supplier in response to differences in pressure existent between the suction and discharge of said pump at times during each cycle of operation.

21. A pumping system comprising, in combination, a pneumatic pressure chamber, a pump casing having an impeller for supplying liquid to said chamber, said casing being substantially wholly enclosed by said chamber, means for starting and stopping the pump to define a cycle of pump operation, an air supplier for said chamber, and means for actuating said air supplier in response to differences in pressure existent between the suction and discharge of said pump at times during each cycle of operation.

22. A pumping system comprising, in combination, a pneumatic pressure chamber, a pump

13

having an impeller for supplying liquid to said chamber, means for starting and stopping the pump to define a cycle of pump operation, an air supplier for said chamber, means for actuating said air supplier in response to differences in pressure existent between the suction and discharge of said pump at times during each cycle of operation, and means for maintaining a quantity of air in said chamber.

23. A pumping system comprising, in combination, a pneumatic pressure chamber, a pump having an impeller for supplying liquid to said chamber, means for starting and stopping the pump to define a cycle of pump operation, an air supplier for supplying air to said chamber, said air supplier including a moveable element urged in the one direction by the pressure existent on the discharge side of the pump and urged in the opposite direction at least partly by mechanical pressure.

24. A pumping system comprising, in combination, a pneumatic pressure chamber, a pump having an impeller for supplying liquid to said chamber, means for starting and stopping the pump to define a cycle of pump operation, an air supplier for supplying air to said chamber without passing through the pump and once during each cycle of operation of the pump, said air supplier including a moveable element urged in the one direction by the pressure existent on the discharge side of the pump and urged in the opposite direction at least partly by mechanical pressure.

25. A pumping system comprising, in combination, a pump casing having a rotatable impeller mounted therein, a chamber by which the pump casing is enclosed and into which liquid is discharged from said casing by the impeller, means for supplying air to said chamber, means for retaining in the chamber adjacent the top thereof a volume of air under pressure while liquid is supplied to a point of use from the chamber, and means for retaining in the chamber at all times a sufficient quantity of liquid to maintain the pump casing sufficiently full of liquid to insure priming of the pump.

26. A pumping system comprising, in combination, a pump casing having a rotatable impeller mounted therein, a chamber by which the pump casing is enclosed and into which liquid is discharged from said casing by the impeller, means for controlling the pressure within the chamber between upper and lower limits, means for supplying air to said chamber without passing through the pump, means for retaining in the chamber adjacent the top thereof a volume of air under pressure while liquid is supplied to a point of use from the chamber, and means for retaining in the chamber at all times a sufficient quantity of liquid to maintain the pump casing sufficiently full of liquid to insure priming of the pump.

27. A pumping system comprising, in combination, a pump casing having a rotatable impeller mounted therein, a chamber by which the pump casing is enclosed, a jet pump, said system having connections whereby the system is connected to a source of supply and liquid enters the jet pump from said source, then passes to the impeller pump and then passes to the chamber with a portion of the liquid from the chamber returning to the jet pump for supplying energy thereto and the remainder flowing from the chamber to a point of use of the liquid, means for supplying air to said chamber, means for retaining in the chamber adjacent the top thereof a volume of air under pressure, and means for retaining in the chamber at all times a sufficient

14

quantity of liquid to maintain the impeller pump casing sufficiently full of liquid to insure priming of the system.

28. A pumping system comprising, in combination, a pump casing having a rotatable impeller mounted therein, a chamber by which the pump casing is enclosed, a jet pump, said system having connections whereby the system is connected to a source of supply and liquid enters the jet pump from said source, then passes to the impeller pump and then passes to the chamber with a portion of the liquid from the chamber returning to the jet pump for supplying energy thereto and the remainder flowing from the chamber to a point of use of the liquid, means for controlling the pressure within the chamber between upper and lower limits, means for supplying air to said chamber without passing through the impeller pump, and means for retaining in the chamber at all times a sufficient quantity of liquid to maintain the impeller pump casing sufficiently full of liquid to insure priming of the system.

29. A pumping system comprising, in combination, a pump casing having a rotatable impeller mounted therein, a chamber by which the pump casing is enclosed, a jet pump, said system having connections whereby the system is connected to a source of supply and liquid enters the jet pump from said source, then passes to the impeller pump and then passes to the chamber with a portion of the liquid from the chamber returning to the jet pump for supplying energy thereto and the remainder flowing from the chamber to a point of use of the liquid, means for supplying air to said chamber without passing through the impeller pump or the jet pump, means for retaining in the chamber adjacent the top thereof a volume of air under pressure, and means for retaining in the chamber at all times a sufficient quantity of liquid to maintain the impeller pump casing and the jet pump sufficiently full of liquid to insure priming of the system.

30. In combination with a pump and storage tank therefor, an air charging means comprising a reciprocating pressure responsive element adapted for connection to the discharge and intake passages of said pump and motivated by the pressure differential generated by said pump when in operation, and a reciprocating air pump element connected to and motivated by said first element and having an air discharge passage adapted for connection to said tank.

31. An air charger for a pump and storage tank comprising, a body formed with relatively high and low pressure chambers, a movable element mounted between said chambers and displaced by the pressure differential therein, means for connecting said chambers to an external source of pressure differential, an air chamber in said body, a volumetric displacement member in said air chamber, means connecting said member to said element for joint movement, and an air intake and discharge means connected to said air chamber, said air discharge means being connected to said high pressure chamber.

32. In a pump and storage tank system, the combination of a pump having intake and discharge passages developing therebetween a pressure differential during operation of the pump; and an air charger comprising a body having relatively high and low pressure chambers, means for connecting said chambers to said pump passages, a movable element mounted between said chambers and displaced by the pressure differential therein, an air chamber in said

15

body, a volumetric displacement member in said air chamber, means connecting said member and element, and air intake and discharge means connected to said air chamber, said air discharge means being connected to said pump discharge passage.

33. A pumping system comprising, in combination, a pneumatic pressure chamber, a pump having an impeller for supplying liquid to said chamber and defining a suction side of the system and a pressure side of the system, means for starting and stopping the pump to define a cycle of pump operation, motor means having opposite sides, one of which is exposed to the suction side of the system and the other of which is exposed to the pressure side of the system, said motor means being moved in one direction by the differential in pressure between the suction and pressure sides when the pump is operating, means for moving the motor means in the opposite direction when the pump is at rest, a movable element connected to and actuated by said motor means, said movable element having opposite sides one of which is exposed to said pressure side of the system, said movable element having a smaller area of exposure to the pressure side of the system than said motor means and means on the other side of said movable element for drawing in atmospheric air and discharging it into said pneumatic pressure chamber.

34. A pumping system comprising, in combination, a pneumatic pressure chamber, a pump having an impeller for supplying liquid to said chamber and defining a suction side of the system and a pressure side of the system, means for starting and stopping the pump to define a cycle of pump operation, motor means having opposite sides, means for connecting one of said sides to a part of the system which when the pump is operating is always at a pressure above atmospheric pressure and means for connecting the other of said sides to a part of the system which when the pump is operating is always at a pressure less than the pressure to which the first side is exposed, said motor means being moved in one direction by said differential in pressure when the pump is operating, means for moving the motor means in the opposite direction when the pump is at rest, a movable element connected to and actuated by said motor means, said movable element having opposite sides one of which is exposed to said pressure side of the system, said movable element having a smaller area of exposure to the pressure side of the system than said motor means and means on the other side of

16

said movable element for drawing in atmospheric air and discharging it into said pneumatic pressure chamber.

35. A pumping system comprising, in combination, a pneumatic pressure chamber, a pump having an impeller for supplying liquid to said chamber and defining a suction side of the system and a pressure side of the system, a jet pump, connections for supplying liquid to said jet pump from said chamber and for discharging liquid from said jet pump to said impeller pump, means for starting and stopping the impeller pump to define a cycle of pump operation, motor means having opposite sides one of which is exposed to the suction side of the system and the other of which is exposed to the pressure side of the system, said motor means being moved in one direction by the differential in pressure between the suction and pressure sides when the impeller pump is operating, means for moving the motor means in the opposite direction when the impeller pump is at rest, a movable element connected to and actuated by said motor means said movable element having opposite sides one of which is exposed to said pressure side of the system, said movable element having a smaller area of exposure to the pressure side of the system than said motor means and means on the other side of said movable element for drawing in atmospheric air and discharging it into said pneumatic pressure chamber.
